UNITED STATES PATENT OFFICE.

EMMA READ, OF SPOKANE, WASHINGTON.

PORABLE BABY FENCE.

Application filed April 29, 1922. Serial No. 557,307.

To all whom it may concern:

Be it known that I, EMMA READ, a citizen of the United States, residing at Spokane, in the county of Spokane and State 5 of Washington, have invented certain new and useful Improvements in Portable Baby Fences, of which the following is a specification, reference being had to the accompanying drawings.

10 It is the purpose of the present invention to provide a device of this character for the protection of young children, preferably babies ranging from one to three and a half years old.

15 It has been found that children around this age more or less get into trouble, fall and hurt themselves, especially when not in the actual care of an older person, such as a nurse or the mother, or others. Furthermore mothers and nurses, and others 20 who are in charge of children of this age have other duties to perform around the house, and if they are required to divide their attention, the children are very apt to 25 get into mischief, and as previously stated fall and hurt themselves.

It is, therefore, the purpose of the present invention to provide a portable baby fence, which may be arranged on the floor, 30 on the front lawn or the like, or preferably upon a bed, so that the babies may be placed on the inside of the fence with their toys, and be left to play with safety, while the parents or others in charge can attend to their duties 35 in the house.

It is another purpose to provide a baby fence of this character, which is foldable into a small compass, and portable from one place to another, so that when the family 40 is out camping the parents may rest assured that the baby cannot get hurt, due to the fact of erecting the fence around a requisite size piece of canvas, for the protection of the baby.

45 Still another purpose is the provision of a foldable portable baby fence, which when folded may be neatly wrapped in a heavy piece of canvas, which acts as a covering for the lawn or bed clothing, and upon 50 which the baby may play, without soiling the covers of the bed, and without soiling the baby's clothes when the canvas is arranged upon the lawn. The canvas also acts to protect the children from the cold ground; 55 when used as a wrapping for the fence when folded, it may be neatly arranged and

strapped so that the fence may be easily carried from one place to another, as it is the aim to construct it from relatively light material.

60 A further purpose is the provision of a baby fence, wherein foldable hollow corner sections are provided, which are adapted to receive the collapsible fence sections, the top and bottom rails of which are subsequently foldable upon the edges of the corner sections, thereby closing the corner sections and protecting the folded fence sections which are located therein, when the fence is folded in a small compass and 70 wrapped with a canvas cover.

65 A still further purpose is the provision of means for detachably connecting the fence sections, so that the sections may be separated for folding into the respective fence 75 corners.

Furthermore it is the aim to provide means carried by the lower rails of the fence for attaching the fence to the side angle 80 iron of a bed.

85 It is to be understood that the particulars herein given are in no way limitative and that while still keeping within the scope of the invention, any desired modifications of detail and desired proportions may be made in the apparatus according to circumstances.

The invention comprises further features and combination of parts, as will be herein-after set forth, shown in the drawings and claimed.

90 In the drawings:—

Figure 1 is a plan view of the improved foldable portable baby fence constructed in accordance with the invention;

Figure 2 is a side view of the same;

95 Figure 3 is a perspective view of one of the corner sections of the fence, showing portions of the fence sections proper to be folded within the hollow corner sections;

Figure 4 is a perspective view of the four 100 sections of the fence placed together to be wrapped;

Figure 5 is a similar view, showing other faces of the sections when so placed together;

Figure 6 is a perspective view showing the baby fence collapsed and wrapped in the 105 canvas bed cover;

Figure 7 is a detail view of one of the fence palings.

Referring to the drawings, 1 designates the entire baby fence, which comprises four 110

corner sections 2. Each corner section comprises two hollow parts 3 and 4. The hollow part 3 constitutes a part of the side of the fence, while the hollow part 4 constitutes a part of the end of the fence. As previously stated these parts 3 and 4 are hollow and attached therein as at 5 are the corner ends of the fence sections 6. The hollow parts 3 and 4 of each corner section 10 may be constructed of any suitable material, either wood or metal preferably the latter, in order to insure strength and durability. In fact the parts of the corner sections are made of light sheet metal, preferably aluminum, and are hingedly united as at 7, so that the parts are capable of folding upon each other, as disclosed in Figure 4 of the drawing.

Each fence section 6 comprises a plurality 20 of vertical palings 8, which are linked together by the upper and lower link chains 9 and 10. The links of these chains are of lengths equal to the thickness of each hollow part of a corner section, in order to permit the fence section to fold or collapse 25 within the hollow part.

When the fence is in use the end links of one set of chains of one fence section are connected to the corresponding links of the 30 other set of chains of another fence section, by means of suitable snap hooks 11, which hold the sections securely connected, and in such wise as to prevent the baby from detaching the hooks.

Each fence section also includes upper and lower rails 12 and 13, which are pivoted to a hollow part of the corner section as at 14. The upper and lower railings 12 and 13 are channel shaped in cross section for 40 the reception of the upper and lower ends of the palings of the fence section, in order to permit the palings to slide therein. When taking down the fence, the snap hooks 11 are unfastened, then the palings and their 45 chains are collapsed into the hollow parts of the corner sections, and then the upper and lower channel rails 12 and 13 are folded, to close the open ends of the parts 3 and 4 of the corner sections. In fact each lower 50 rail is folded upwardly, while each upper rail is folded downwardly. In practice the baby fence is to be made of a height equal to the length of the upper and lower channel rails 12 and 13 of the sides of the fence, 55 so that when the upper and lower channel rails 12 and 13 are folded, they completely cover or close the open ends of the parts 3 and 4 of the corner sections of the fence. However the upper and lower channel rails 60 12 and 13 of the end fence sections proper are shorter than the upper and lower rails 12 and 13 of the side fence sections. While these shorter upper and lower rails do not entirely cover the open ends of the parts 4 65 of the corner sections, so that the upper rail

will entirely cover the lower rail, they do act to fold in a neat manner, so that the fence may be taken down and collapsed and arranged in a small compass.

When the fence is in use, the ends of the 70 upper and lower fence rails 12 and 13 are bolted together securely by means of square bolts 15 mounted in the rails.

The lower edges of the corner sections are provided with clamps 16, which are adapted 75 to engage the angle rails of a bed, when the fence is mounted thereon. An area of canvas 17 sufficient to fit within the fence when in use and to cover the bed clothing to keep it from being soiled is provided. The edges 80 of the canvas are provided with snap hooks 18, for connecting the canvas to the fence. When the fence is collapsed or folded, the corner sections are folded together and arranged as shown in the drawings, it may be 85 wrapped within the canvas, and then subsequently strapped, so that the fence may be carried from one place to another and have the appearance of a suit case.

The invention having been set forth, what 90 is claimed is:—

1. A foldable portable baby fence, comprising hingedly collapsible corner sections, side and end fence sections collapsible within the foldable corner sections, and means 95 for connecting the adjacent ends of the fence sections, when the fence is erected.

2. A foldable portable baby fence, comprising hingedly collapsible corner sections, side and end fence sections collapsible within the foldable corner sections, and means 100 for connecting the adjacent ends of the fence sections, when the fence is erected, said side and end fence sections comprising upper and lower rails, said rails being channelled for the reception of the upper and lower ends of the palings of the side and end sections whereby the palings of the end and side fence sections may slide 105 downwardly when the fence is collapsed. 110

3. A foldable portable baby fence, comprising hingedly collapsible corner sections, side and end fence sections collapsible within the foldable corner sections, and means for connecting the adjacent ends of the fence sections, when the fence is erected, said side and end fence sections comprising upper and lower rails, said rails being channelled for the reception of the upper and lower ends of the palings of the side and end sections, whereby the palings of the end and side fence sections may slide downwardly when the fence is collapsed, said upper and lower railings of the side and end fence sections being hingedly connected to the 115 corner sections and being foldable to close the corner sections. 120

4. A portable foldable baby fence comprising corner sections, said corner sections comprising hingedly connected foldable hol- 130

low parts, side and end fence sections connected to the interior of and collapsible within the hollow parts of the corner sections, said side and end fence sections comprising channel rails in which the upper and lower ends of the palings of the side and end fence sections are slidably engaged, said upper and lower channel rails being hingedly connected to the hollow parts of the fence sections and collapsible to folded positions to close the hollow parts of said corner sections.

5. A portable foldable baby fence comprising corner sections, said corner sections comprising hingedly connected foldable hollow parts, side and end fence sections connected to the interior of and collapsible within the hollow parts of the corner sections, said side and end fence sections comprising channel rails in which the upper and lower ends of the palings of the side and end fence sections are slidably engaged, said upper and lower channel rails being hingedly connected to the hollow parts of the fence sections and collapsible to folded positions to close the hollow parts of said corner sections, means for connecting the adjacent ends of the side and end fence sections when the fence is erected, and means connected to the corner sections for attaching the fence on the side rails of the bed.

tions, means for connecting the adjacent ends of the side and end fence sections when the fence is erected.

6. A portable foldable baby fence comprising corner sections, said corner sections comprising hingedly connected foldable hollow parts, side and end fence sections connected to the interior of and collapsible within the hollow parts of the corner sections, said side and end fence sections comprising channel rails in which the upper and lower ends of the palings of the side and end fence sections are slidably engaged, said upper and lower channel rails being hingedly connected to the hollow parts of the fence sections and collapsible to folded positions to close the hollow parts of said corner sections, means for connecting the adjacent ends of the side and end fence sections when the fence is erected, and means connected to the corner sections for attaching the fence on the side rails of the bed.

In testimony whereof I hereunto affix my signature.

EMMA READ.
